UNITED STATES PATENT OFFICE

2,478,492

ICE ELIMINATING SYSTEM

Donald M. Lawrence, Caldwell, N. J., assignor to
 Bendix Aviation Corporation, South Bend, Ind.,
 a corporation of Delaware

Application January 30, 1942, Serial No. 428,948

11 Claims. (Cl. 244—134)

1

This invention relates to ice eliminating systems, and particularly to a system for removing ice from the leading edges of aircraft surfaces.

Prior to the present invention, it has been common to utilize rubber tubes or boot elements along the leading edges of aircraft wings and tail surfaces in order to break up accumulations of ice on these surfaces and permit the ice to be carried away by the air stream.

In the patent to Gregg, 1,990,866, there is described an ice eliminating system wherein rubber boots are inflated in accordance with a definite cycle of operation, the air from one inflated boot being directed by a distributing valve into a second inflatable boot, until the pressure in the two boots is equalized. Upon equalization of air pressure in the boots, additional air from a pressure pump is directed into the second boot to complete the inflation. The present invention is an improvement over the system described in the Gregg patent, and is directed to a novel air distributing means and method whereby the elimination of ice may be expedited.

In the present invention the distributor valve is so arranged as to first port air under pressure to the selected boot for a first predetermined time interval, then to close off the air pressure and for a second predetermined time interval, controlled by the speed of the motor and by the size of the port opening, to port the air under pressure in the boot to the atmosphere, thereby allowing a portion of the air to flow out of the inflated boot. The valve then closes the port to the atmosphere, and opens a port connected to a source of suction for a third predetermined time interval. This then evacuates the boot and holds it to the airfoil contour. The action of first dumping some of the air from the boot overboard to atmosphere thereby reduces the quantity of air to be forcibly evacuated from the boot through the suction or vent line.

It is an object of the present invention to provide an ice eliminating system for aircraft employing inflatable boot members, wherein the boot is first inflated, then deflated, and finally, placed under suction in separate steps for predetermined time intervals.

It is a further object of the invention to provide a system wherein a boot member is subjected to the cycle of inflation to a superatmospheric pressure, deflation to atmospheric pressure, and connection to a source of sub-atmospheric pressure in separate phases.

Yet another object of the invention is the pro-

2

vision of a novel distributing member for carrying out the above novel system.

According to the invention, there is provided a distributor particularly designed for use with inflatable boots for the elimination of ice from aircraft and adapted when actuated to connect each chamber of a plurality of boot chambers controlled thereby cyclically to a source of fluid pressure, to atmosphere, and to a source of suction, wherein when the pressure source is cut off and the distributor arrested all of the boots are connected to the suction source. The improved distributor may be operative to connect each chamber of a plurality of chambers one after the other to a source of fluid pressure or the atmosphere and all of the chambers simultaneously to a source of suction whereby, when the source of pressure is eliminated, all of the chambers will be evacuated.

20 Other objects will appear from a study of the following specification when made in conjunction with the attached drawings, throughout which like numerals designate like parts.

Fig. 1 is a schematic showing in plan of one 25 installation of the system of the present invention.

Fig. 2 is a view, partly in elevation and partly in section, of the novel distributing valve of the present invention.

30 Fig. 3 is a cross-sectional view taken along the line 3—3 of Fig. 2.

Fig. 4 is an end elevational view of the distributing valve of the present invention.

Fig. 5 is a perspective of the valve element 35 which is incorporated into the distributor valve assembly of the present invention;

Fig. 5A is an end elevational view of the valve element shown in Fig. 5; and

40 Figs. 6 and 7 are sectional views of the distributing valve in two different positions in its cycle of operation.

In general, the invention includes the method, and the means for carrying out the method, wherein a boot element is first inflated with air 45 from a pressure source, then deflated to atmospheric pressure, and thereafter, opened to a source of suction for maintaining the boot interiors at low pressure to prevent boot vibration or boot expansion at low atmospheric pressures.

50 As shown in Fig. 1, 10 is an aircraft, shown in phantom, having wing members 11 and 12, motors 13 and 14, and tail section 15. Each of the wings contains a series of laterally extending tubular boot members along its leading edge, as 55 will be readily understood. Wing 11 contains a

plurality of groups of such tubular members, designated 16, 17, 18, 19, 20, 21, and wing 12 contains corresponding groups 16' to 21'. Each of these groups extends for a definite portion of the wing span. For example, the tubular members in groups 16 and 16' extend to the wing tip, groups 21 and 21' extend inwardly to the fuselage, and each of the other groups extends outwardly to the next adjacent group. The additional groups 22 and 22' of tubular members extend along the leading edge of each side of the horizontal stabilizer of the tail portion 15, and another group 23 extends along the leading edge of the vertical stabilizer or rudder post of the tail portion 15. The different wing groups of inflatable members have connection to particular ports of air distributors 24 and 25 through air ducts 26, and the different groups of inflatable members on the tail portion 15 have connection to particular ports of an air distributing valve 27 through the air ducts 28. Since it is impossible to show the ice eliminating system in true scaled relation to the aircraft 10, the different groups of inflatable members which extend along the leading edge of the wings and the tail surfaces are shown as distributed rather largely over the surface of the craft, and the air ducts are represented schematically after the fashion of an electrical wiring diagram.

Engine 13 drives a pressure pump 29 and a suction pump 30, and engine 14 drives a pressure pump 31 and a suction pump 32. Pumps 29 and 31 are connected through their respective conduits 33 and 34 to a junction member 35, from which a single pressure distributing line 36 extends rearwardly of the junction member 35. Pumps 30 and 32 are joined to another portion of junction member 35 through their respective conduits 37 and 38, and a single suction line 39 extends rearwardly from a T connection taken from the joined suction conduits 37 and 38. The main pressure line 36 has a connection, which will be better understood from a later description of the air distributing valves, to the distributing valves 24 and 25, and also a similar connection to the distributing valve 21. Suction line 39 has connections to the distributing valves 24, 25 and 21 in a manner which will also be apparent from the later description of the distributor valves. Further, a check valve 40, through which air may be drawn to a low pressure point exteriorly of the plane, opens to suction line 39.

Particular reference to Figs. 2, 3 and 4 should be had for a description of the air distributing valves 24, 25 and 21. Since these units are basically similar, the description will be confined to one, valve 24. An electric motor 41, which may be driven by the craft power supply that may be connected to the motor at the terminal post 42, controls the rotation of a shaft 43 extending within the housing 44 of the distributing valve, which housing contains speed reduction units, such as a plurality of worm and gear drives 45, which rotate the transverse shaft 46 at a suitably slow speed for the proper distribution of air to the inflatable boot members. A generally cylindrical rotatable valve 47, which is clearly shown in perspective in Fig. 5, is contained within each of the distributing heads 48 and 49, and is driven by the transverse, double-ended shaft 46, keyed to the last gear of the speed reduction unit 45.

Distributing heads 48 and 49 are identical, and each includes a cylindrical body portion 51, from which five obliquely extending, radial ports or boot connections 52 project. Each of these boot

connections is open to a particular rubber boot or series of boots through conventional air tubing, not shown in Fig. 2, but indicated schematically as one of the tubes 26 or 28 in Fig. 1. Body portion 51 is fitted with an interior metal liner 53, against which the outer surface of the cylindrical valve 47 is rotated by motor 41. This liner 53, as well as the body portion 51, has a port opening 54 placed under each of the boot connections 52. Liner 53 also has a single suction connection 55, which opens into a manifold space 56 extending throughout the circumference of body portion 51. A series of port openings 57, equally spaced about the circumference of liner 53, falls within the manifold space 56 in line axially with the series of port openings 54.

Each of the distributing heads 48 and 49 carries an axially extending atmospheric air port connection 58, and this connection 58, along with body portion 51, is secured to a central housing and standard 59, by means of a series of studs-bolts 60. A check valve 61 is shown closing air exhaust port 62, and a spring member 63 urges valves 61 closed, although, as will be later shown, air under certain conditions will cause valve 61 to be swung about its pivot 64 to open position. The central housing portion 59 contains an air inlet 65, which opens into distributing heads 48 and 49 through circular apertures 66.

Considering Fig. 5 along with Fig. 2, it will be seen that valve member 47 has an end port 67 opening axially of valve 47, through which air under pressure from a pressure pump may flow from air inlet 65 to be distributed in the manner that will be described later. A second axial opening 68 is formed in the outer wall 69 of valve 47. Opening 68 forms an air exhaust passageway for the dumping of air overboard to atmosphere through check valve 61 and port connection 58. Three more ports, all opening radially, are contained in valve 47. The largest of these port openings 70, extends axially a sufficient length to establish air-flow between any two aligned ports 54 and 57 in the liner 53. The next largest port opening 71, is axially coextensive with the port openings 54 in liner 53. The last radial opening in valve 47, namely, port opening 72, extends axially for the same distance as port opening 71, but is of considerably less extent circumferentially, as will be pointed out later. The circumferential extent of each of apertures 70, 71 and 72 bears a definite relation to each other and to the cycle of operation, which consists of the inflation of a boot, the dumping of air from the boot to the atmosphere, and the opening of the boot to the suction pump, which cycle is carried out in one revolution of valve 47 for each of the five boot ports 52.

The cycle can be readily understood after considering the rotation of the valve and the distribution of air with respect to one of the boot connections 52, for example, the top boot connection shown in section in Fig. 2. Considering valve 47 to be rotated clockwise, as shown in Fig. 5, port opening 71 will pass under the top boot connection 52 at a fixed speed, depending upon the initial speed of motor 41 and the train value of the reduction gearing 45. While port opening 71 is in communication with this boot connection 52, air is being admitted under pressure to the boot connected thereto from the pressure line 36 through the air inlet 65 in connection therewith, and through the ports 66 and 67. As port opening 71 is rotated past the top boot connection 52, the cylindrical surface of valve 47 will seal con-

nection 52, maintaining the boot inflated until port opening 72 comes under boot connection 52. For an interval determined by the speed of the valve 47 and the angular size of port opening 72, the air under pressure from the boot will be opened to the atmosphere through port 68, check valve 61 and atmospheric air connection 58. The boot pressure will therefore drop until it equals the atmospheric pressure, at which point check valve 61 will close and prevent atmospheric air from entering the boot connection 52. Port opening 72 will have then passed completely out of communication with top boot connection 52, and this connection will be placed in communication with the suction connection 55, which, of course, is in circuit with suction line 39. During the interval when port 70 maintains boot 52 in communication with the suction pump through suction connection 55, air will be drawn out of the boot, maintaining it flattened against the surface of the wing or tail surface to which it is applied, thus preventing the vibration and flutter caused by its proximity to a low pressure area, which vibration and flutter result in a decreased effectiveness of the wing surface, and a shortened life for the boot element.

The cycle just described is repeated for each of the five boot connections 52 during one revolution of distributor valve 47. A normal speed of operation may be one revolution of valve 47 in forty seconds, and the port openings 70, 71 and 72 will be adjusted in size to fit a particular installation of boot elements. It is intended that all boot elements not being inflated through port opening 71, or dumped to atmosphere through port opening 72 and port 68, shall be placed under suction through port 70 and suction connection 55, and therefore, port 70 should be large enough in circumferential extent to place three boots under suction at any one time.

When the motor-driven valves 24, 25 and 27 are not in operation, all the boot connections are placed under suction. In the arrangement shown in Figure 1 the junction member 35 has connected thereto the pressure conduits 33 and 34 and suction conduits 37 and 38. The junction member 35 includes a suitable gate or control valve for alternately connecting the pressure lines 33 and 34 or the suction lines 37 and 38 to the distributor line 36. Thus when the motor driven valves 24, 25 and 27 are not in operation the valve 35 may be shifted so as to close or disconnect the pressure lines 33 and 34 from the distributor line 36 and open or connect the suction lines 37 and 38 to the distributor line 36. The control valve may be adjusted manually or may be positioned by suitable power means.

The source of suction is, of course, the engine-driven pumps 30 and 32, aided by the branch line carrying check valve 40, which, opening outside of the craft at a point of low aerodynamic pressure, will cause the pressure in line 39 to be maintained at a sufficiently low value to keep the boot elements tightly against the skin of the craft, thus eliminating the flutter and vibration of boots employed in the conventional system, such as that shown in the Gregg patent above identified. So that the particular boot connection under which aperture 71 falls when the system is stopped may be placed under suction, the small slots 73 are provided so that in the "off" position, there may be a continuous sucking of air from the boot connection 52, under which port opening 71 stops. In order that the boot connection under which port opening 72 stops may also

be open to suction, a small hole 74, as shown in Fig. 2, is drilled in the wall between port openings 71 and 72. Slots 73 and opening 74 are so small that during operation of the ice eliminating system, they do not offer substantial interference with the inflating of the different boot members 52, and thus, each of the port openings 70, 71 and 72 is effectively isolated or chambered from the other two.

The foregoing may also be accomplished by arranging the rotary valve 47, as shown in Figure 6, so that at the opening 72 the rotary valve 47 is spaced slightly from the liner 53 and thereby provides a restricted passage between the rotary valve 47 and the liner 53 extending from the opening 57 to the openings 52 and 72. Thus after the super atmospheric pressure has been exhausted from the connected boot through the valve opening 68 and valve 61 has closed the same, suction may be applied to the boot through the latter restricted passage between the rotary valve 47 and liner 53.

It will be seen, moreover, that if the valve 47 be stopped in the latter position and the super atmospheric pressure be terminated through line 36 without the connection of the suction lines 37 and 38 thereto, then suction may be applied through the restricted passage 74 to port 71 and slots 73 and the boot connected thereto, as well as to the boots connected to openings 70 and 72.

Thus all of the boot connections may be effectively placed under suction, when the system is not in normal operation.

While only one embodiment of the present invention has been shown in the drawing, it is to be understood that various changes may be made without departing from the scope of the present invention. For this reason, it is intended not to limit the invention by the description herein given as an example, but solely by the scope of the appended claims.

What is claimed is:

- An air distributing device comprising a housing, a cylindrical valve chamber, a rotatable valve therein, said valve having a cylindrical surface, means for rotating said valve, an axially disposed air inlet port to said valve, a plurality of radially disposed boot ports formed in said housing, a plurality of suction ports equal in number to said boot ports and axially aligned therewith, said suction ports opening into a manifold, a suction outlet in communication with said manifold, an axially disposed air exhaust port formed in said housing, a check valve disposed over said air exhaust port and biased to prevent re-entry of exhausted air, a first valve aperture formed in the cylindrical surface of said valve in registry with each of said boot ports in succession, said first valve aperture being in communication with said air inlet port, a pair of valve apertures, one formed in said cylindrical surface for successive registry with each of said boot ports and the other formed axially for communication with said air exhaust port, a dividing wall formed in said valve for isolating said first valve aperture from said pair of valve apertures, an additional valve aperture in said cylindrical surface, said additional aperture disposed for simultaneous registry with one of said boot ports and one of said suction ports, and means formed in said valve for isolating said additional valve aperture from said air inlet port, from said first valve aperture, and from said pair of apertures.
- An air distributing device for use with inflatable boots for the elimination of ice from an

aircraft, comprising a housing having a valve chamber, a valve rotatable therein, said valve being divided into three separate compartments, an air inlet port in said housing opening into said chamber, an air exhaust port, a plurality of ports for connection to said boots, and a suction port means opening into said chamber, one of said compartments providing communication between one of said boot ports and said air inlet port, the second of said compartments providing separate communication between one of said boot ports and said air exhaust port, the third of said compartments providing separate communication between one of said boot ports and said suction port means, and means for rotating said valve to provide a predetermined sequence of connections between the boot ports and the other ports.

3. An air distributing device for use with an inflatable boot for the elimination of ice from an aircraft, comprising a housing, a cylindrical valve chamber therein, a cylindrical rotatable valve in said chamber, a port for connection to said boot, an air inlet port, an air exhaust port, and suction port means in said housing, all opening into said valve chamber, said air inlet and said air exhaust ports being located at opposite ends of said chamber, axially thereof, said valve having one compartment containing apertures registerable with said boot port and said air inlet port, a second compartment having apertures registerable with said boot and said air exhaust port, a third compartment having an aperture registerable with said boot port and said suction port means, and means for rotating said valve to provide a predetermined sequence of connections between the boot port and the other ports through said apertures.

4. An air distributing device comprising a housing, a cylindrical valve chamber, a rotatable valve therein, said valve being generally hollow with a cylindrical valve surface, a plurality of radially disposed air distributor ports opening into said chamber, suction port means, air inlet port means and air exhaust port means opening into said chamber, a check valve disposed over said air exhaust port means and biased to prevent re-entry of exhausted air, a first pair of apertures formed in said valve, registerable, respectively, with one of said air distributor ports and said air inlet port, a second pair of apertures formed in said valve and registerable, respectively, with one of said air distributor ports and said air exhaust port means, an additional aperture formed in said valve and registerable, respectively, with one of said air distributor ports and said suction port means, and partition means formed in said valve for isolating said additional aperture from each of said pairs of apertures, and said pairs of apertures from each other, and means for continuously rotating said valve so as to effect a predetermined sequence of connections between the air distributor ports and said suction port means, air inlet port means and air exhaust port means.

5. A fluid medium distributing device for use with inflatable ice eliminating members for aircraft, comprising a casing, connections provided on said casing for each of the inflatable members, a pressure fluid inlet connection, an atmosphere connection, and a suction connection, a distributor element in the casing, means to rotate the distributor element, said distributor element operative when rotated to connect each inflatable member cyclically with the pressure fluid, the

atmosphere and the suction connections, and said distributor element including means whereby upon the pressure fluid connection being interrupted and rotation of the distributor element being arrested, the distributor may connect all of the inflatable members to a source of suction.

6. A fluid medium distributing device for use with inflatable ice eliminating members for aircraft, comprising a casing, connections provided on said casing for each of the inflatable members, a pressure fluid inlet connection, an atmosphere connection, a suction connection, a distributor element, means to rotate the distributor element, the distributor element including a first compartment adapted to register successively each inflatable member connection with the pressure fluid connection, a second compartment adapted to register successively each inflatable member connection with the atmosphere connection, and a third compartment adapted to register successively each inflatable member connection with the suction connection, said distributor element also including means whereby upon the pressure fluid connection being interrupted and rotation of the distributor element being arrested the distributor may connect all of the inflatable members to a source of suction.

7. A system for the removal of ice from airfoil surfaces of aircraft, comprising, an inflatable boot, first means providing a source of a fluid medium under super atmospheric pressure, second means providing a source of suction, means operable selectively to connect said boot to said source of super atmospheric fluid pressure to inflate said boot and to connect said boot to atmosphere to deflate said boot, check valve means to control the atmosphere connection so as to permit fluid medium under super atmospheric pressure to exhaust from the boot, but precluding re-entry of said fluid medium from the atmosphere, and restricted fluid conduit means between said boot and said source of suction for deflating said boot under suction upon said super atmospheric fluid pressure being exhausted from said boot through said atmosphere connection.

8. A fluid medium distributing device comprising, a casing, a plurality of fluid distributor connections provided on said casing, a pressure fluid inlet connection to the casing, an atmosphere connection to the casing, a suction connection, a distributor element in the casing, means to rotate the distributor element, the distributor element including a first compartment adapted to register successively each fluid distributor connection with the pressure fluid connection, a second compartment adapted to register successively each of the fluid distributor connections with the atmosphere connection, and a third compartment, a manifold for said casing and having suction ports equal in number to and axially aligned with the fluid distributor connections, said suction connection opening into said manifold, said third compartment adapted to successively register with the axially aligned suction ports and fluid distributor connections, and means including a restricted passage connecting said first and second compartments, whereby upon the pressure fluid connection being interrupted and rotation of the distributor element being arrested the distributor element may connect all of the fluid distributor connections to a source of suction.

9. A fluid medium distributing device, comprising, a casing, a plurality of fluid distributor connections provided on said casing, a pressure fluid

inlet connection to the casing, an atmosphere connection to the casing, and a suction connection, a distributor element in the casing, means to rotate the distributor element, the distributor element including a first compartment adapted to register successively each fluid distributor connection with the pressure fluid connection, a second compartment adapted to register successively each of the fluid distributor connections with the atmosphere connection, and a third compartment, a manifold for said casing and having suction ports equal in number to and axially aligned with the fluid distributor connections, said suction connection opening into said manifold, said third compartment adapted to successively register with the axially aligned suction ports and fluid distributor connections, and means including a restricted passage connecting said first and second compartments, whereby upon the pressure fluid connection being interrupted and rotation of the distributor element being arrested the distributor element may connect all of the fluid distributor connections to a source of suction, and a check valve in the atmosphere connection for permitting fluid under super atmospheric pressure and returning through one of said fluid distributor connections to exhaust while preventing passage of fluid medium through the atmosphere connection to said fluid distributor connection.

10. A fluid medium distributing device, comprising, a casing, a plurality of fluid distributor connections provided on said casing, a pressure fluid inlet connection to the casing, an atmosphere connection to the casing, and a suction connection, a distributor element in the casing, means to rotate the distributor element, the distributor element including a first compartment adapted to register successively each fluid distributor connection with the pressure fluid connection, a second compartment adapted to register successively each of the fluid distributor connections with the atmosphere connection, and a third compartment, a manifold provided in said casing, said suction connection opening into said manifold, and said manifold provided with suction ports equal in number to and axially aligned with the fluid distributor connections, said third compartment adapted to successively register with the axially aligned suction ports and fluid distributor connection, and means including a re-

50

stricted communication provided between said first and second compartments, whereby when the source of fluid pressure is cut off and the distributor element is stationary the distributor element may connect all of the fluid distributor connections to a source of suction regardless of the position in which the distributor element comes to rest in its casing.

11. For use with an inflatable element for the removal of ice from airfoil surfaces of an aircraft; a control apparatus comprising, in combination, a unitary housing having an intake port for connection to a source of super atmospheric pressure, an exhaust port for connection to atmosphere, and a port for connection to the element, a valve mechanism in said housing having separate passages connected respectively to said intake and exhaust ports, and said valve mechanism including means operable selectively to connect said element port through said passages to said intake and exhaust ports, check valve means to control the exhaust port so as to permit fluid medium under super atmospheric pressure to exhaust through said exhaust port, but precluding re-entry of said fluid medium from the atmosphere, and restricted fluid conduit means in said valve mechanism and between said element and a source of sub-atmospheric pressure for permitting deflation of said element under sub-atmospheric pressure upon the super atmospheric pressure being exhausted from the element through said exhaust port.
